FIRE ALARM SYSTEM

Samuel Lubin, Pittsfield, Mass., John F. Atkinson, Arlington, Va., and Leon Podolsky, Pittsfield, Mass., assignors to Sprague Electric Company, North Adams, Mass., a corporation of Massachusetts

Application April 23, 1951, Serial No. 222,422

7 Claims. (Cl. 340—287)

1

The present invention relates to fire alarm systems that can be readily and inexpensively installed in smaller cities and towns.

Wired fire alarm systems have become firmly established in modern cities, but prior art systems of this type are relatively expensive; and are beyond the means of most towns. There is accordingly a gap between the age old central fire gong or siren only suited for volunteer fire departments of very small communities, and the standard telegraph type of fire alarm system indispensable for large cities requiring several hundred individual fire alarm signal stations.

Among the objects of the present invention is a fire alarm system of the wired type which can be very readily and inexpensively installed.

Additional objects of the present invention include fire alarm systems that can be used with pre-existing transmission lines without interfering with the normal use of these lines. A further object of the present invention is the provision of a self-monitoring fire alarm system which is reliable in operation.

The above as well as still further objects of the present invention will be more readily understood from the following description of several of its exemplifications, reference being made to the accompanying drawings wherein:

Fig. 1 is a diagrammatic representation of one form of fire alarm system according to the present invention;

Figs. 1a and 1b are simplified somewhat diagrammatic detail views of one type of the signal stations shown in Fig. 1;

Fig. 2 is a schematic view of the essential details of another signal station suitable for use in the embodiment of Fig. 1; and

Figs. 3 and 4 are diagrammatic showings of portions of an indicator assembly suitable for use in the embodiment of Fig. 1.

According to the present invention, there is provided a fire alarm system having a central high frequency current supply station and a plurality of individual signaling stations each including a modulating unit, for connection to a pre-existing electrical line such as a power supply, street lighting line or telephone line, to modulate the high frequency currents. Each station has a different characteristic modulating frequency and externally operable signal control structure connected to the modulating unit for operation to signal a fire alarm by changing the operation of the modulator unit. At the same or a different central location an indicator assembly can be connected to the line to separately indicate the presence of individual modulations and thereby indicate the signaling and the source of specific fire alarms.

Referring to the form of the invention shown in Fig. 1, 10 indicates a portion of a pre-existing

street lighting line, power line or telephone line of a town or small city, the line usually branching over substantially the entire population area. Individual signaling stations are shown at 20 and can be connected at suitably spaced individual locations along the branches of the line. Each station has a remote modulator unit represented by the legend in the figure, and an external signal control handle 22 for operation to signal an alarm. In this embodiment high frequency currents are applied to the line 10 by a carrier current generator 30. At a central location an indicator assembly including a carrier current receiver 40 and an indicator unit 50 are connected to the line to indicate the signaling of a fire alarm.

The carrier current generator can be of any suitable type that impresses upon the line 10 the desired high frequency currents. One highly effective form of such construction is shown in the copending Atkinson et al. U. S. patent application Serial No. 754,422, filed June 27, 1947, and the details of the generator connection there described are hereby incorporated in the present application as though fully set forth herein.

For signaling stations 20, there can be used any type of modulating arrangement to impart one or more characteristic identifiable modulations to the carrier currents. The modulations of the individual stations are conveniently made easily distinguishable from each other by effecting these modulations at different frequencies, as described in the above-mentioned copending application or in the copending Atkinson et al. U. S. patent application Serial No. 171,628, filed July 1, 1950. For distinguishing alarm signals from the indications accompanying equipment failure, the alarm indicating modulations can be coded as by periodic interruptions, or can likewise be represented by differences in modulation frequencies.

Fig. 1a shows one form of coded modulator type of signaling station 20. A toothed wheel 31 is arranged to rotate around a supporting shaft 32 as by any of the well-known fire alarm signal box constructions. Examples of these constructions are shown in U. S. Patent No. 2,343,964 issued to F. C. Evans on March 14, 1944, U. S. Patent No. 2,159,304 granted May 23, 1939, to J. H. Wheelock, and U. S. Patent No. 1,875,810 to G. F. Harter dated September 6, 1932. In the interest of clarity the particular mechanical details for rotating the wheel are not reproduced in Fig. 1a. These constructional features are well known, one common form involving essentially a spring drive that is wound by the manipulation of an alarm signaling handle 22 and then drives the wheel through one or more revolutions. Grooves 36 are shown as distributed around the wheel to coast with a follower 41 which is held against the wheel

as by spring 42 so that it engages and follows the teeth and grooves. A set of contacts 44 is suitably arranged for operation by the follower to actuate the modulator 52, as by leads 45, 46. Whenever the follower drops into a groove 36, the contacts close. Accordingly as the wheel rotates, a sequence of interrupted modulation is effected.

Fig. 1b shows one way of operating a modulator through the contacts 44. The circuit of Fig. 1b is taken directly from the above-identified Atkinson, Kelley and McCutchen applications with the grid lead to the amplification stage broken and the broken ends connected to contact leads 45, 46, respectively. It is preferred that the ground return circuit of this grid be on the grid side of the break so that the grid is never left floating. For a more complete description of the remainder of the modulator, reference should be made to the last-mentioned application. The power supply of Fig. 1b can be the same transmission line 10 to which the modulator output lead is connected, particularly where this line is an electric power supply line. Where line 10 is a conventional low frequency telephone circuit, energizing power can be supplied through this line or by means of an external source local to the signaling station, or by batteries such as the long-lived alkaline amalgamated zinc-mercuric oxide type of dry cell. Electric power supplied over a telephone line can conveniently be of the kind that does not interfere with telephone conversation. Direct currents are quite suitable for this purpose.

Some telephone lines, particularly those having a single separate circuit for each subscriber, do not have an interconnected network but are instead formed of a multiplicity of separate, unconnected individual lines. With this arrangement the central fire alarm station can be conveniently connected to or located at the telephone exchange inasmuch as all the individual telephone lines are connected to this exchange. The desired carrier currents and alarm signals can then be operated through any convenient number of individual lines. To keep the lines separate, they can be coupled through filter circuits that permit passage of the high frequency carriers, but block the transfer of low frequency telephone signals. A small capacitance is all that is needed for such connection. Alternatively, a separate carrier generator can be provided for each line.

At the central station the carrier current receiver 40 and indicator 50 are connected to detect and indicate the alarm modulations, as by audible and/or visual means. A set of simple or conventional demodulator amplifiers similar to those shown in the above-identified copending applications, and a gong actuator is all that is needed. The repeated sounding of a gong will then indicate a fire alarm, and an individual station indicator will show to which location the fire-fighting apparatus should be dispatched.

Should the receiving of modulations be interrupted by reason of equipment failure rather than the signaling of an alarm, only a single sounding of the gong will take place so that the distinction will be unmistakable. In addition the indicator lights will flash on and off only when an alarm is sounded.

If desired, the interrupting wheels 31 of the individual station can be distinctively coded so that the modulation interruptions and the gong sounding will be correspondingly coded to directly indicate the location of the alarm-giving station.

To make it unnecessary for someone to be in constant attendance and accurately note such gong striking, the code wheel is arranged to go through more than one alarm-sounding cycle. The first or second cycle generally attracts sufficient attention so that the third or fourth cycle can be interpreted without difficulty. A tape punching mechanism can also be operated to record the location of the alarm. For this purpose a standard tape puncher can be connected so that it punches in response to each interruption of the modulation from any station. The interruption code will then be reproduced by the punch marks to indicate the source of the alarm.

The signaling station shown in Fig. 2 is operated by modulating the carrier currents at a characteristic and identifiable frequency different at every station. For this purpose it includes an oscillator circuit 195 having a pair of contactless mechanically selective low frequency transfer units 193, 194 connected to an electron-discharge unit 196, for determining specific oscillating frequencies corresponding to the desired modulating rates. Discharge unit 196 is incorporated in an evacuated electron-discharge tube 191 and includes a grounded cathode 197, a control grid 198 and an anode 199. The grid 198 is connected to the cathode by means of grid return resistor 192, and by means of condenser 194 is connected to the movable pole 110 of a single-pole double-throw switch operated by handle 22. The two fixed contacts 111 and 112 of this switch are connected to the common or ground return conductor 120 through the respective output windings 116 of the low frequency transfer units 193, 194. A condenser 198 connects anode 199 in parallel through both of the input windings 117 to ground. A peaking condenser 116 is shown as connected between the switch pole 110 and ground to increase the efficiency of the transfer units by helping to tune their output windings of the oscillating frequencies.

The oscillator is energized by connecting anode 199 through load resistor 131 to the positive lead 111 of a direct current supply 180, the negative terminal of which is grounded as shown. The direct current supply 180 is of conventional form and is shown as a rectifier and filter assembly energized by means of leads 173 from a suitable alternating current power supply to which a filament transformer 178 is also connected for heating filament 190 of stage 196. A voltage regulator shown as a gas diode 134 may be connected across the output of the direct current supply 180 to maintain the oscillator operating under approximately constant voltage. The oscillator 195 develops a sinusoidal voltage which is impressed by means of coupling condenser 136 on the input grid 142 of an amplification stage 140 in the usual manner. From the anode 150 of this stage, amplified oscillations are taken by way of coupling transformer 154 and applied to the anodes 158 of a diode rectifier 160. The cathodes 162 of the rectifier return to ground through an adjustable inductor 166. A capacitor 176 also connects the cathodes to the desired transmission line.

As explained in copending Atkinson et al. U. S. patent application Serial No. 171,628, filed July 1, 1950, the anodes 158 of rectifier 160 are suitably biased by connection through series resistor 168, and voltage dividing resistor 170 to the lead 171 of the direct current supply 180. As also ex-

plained in the last-mentioned patent application, capacitor 176 is arranged to series resonate with variable inductor 166 to the high frequency of the carrier current supplied by carrier current generator to the transmission line 10.

The apparatus of Fig. 2 will apply a varying load to these high frequency currents, as more completely set forth in both of the above Atkinson et al. patent applications and the load variation will be sinusoidal in accordance with the oscillator 195. This oscillation frequency is determined by the mechanically selective characteristics of transfer units 193, 194 which have a pair of matched vibrating magnetic reeds 134, 135 each magnetically linked with the respective windings 117, 118 and mechanically interconnected so that vibrations of one will be transmitted to the other if they correspond very closely in frequency to the natural frequency at which the other will vibrate. The details of several types of such transfer units are more completely set forth in the Atkinson et al. application Serial No. 171,628.

By suitable adjustment and selection, the individual transfer units are arranged to respond and pass only a relatively restricted range of frequencies, the range of any unit being different from that of any other unit in the entire combination of signaling stations. The indicator unit 50 is connected to sharply distinguish the individual modulation ranges, and can have identical transfer units connected for this purpose, as disclosed in the last-mentioned application.

Fig. 3 shows the essential elements of an individual portion of one form of indicator unit of the present invention, suitable for operation with the remote modulator of Fig. 2. A relay 246 is connected by lead 292, fixed contact arm 254, and movable contact arm 248 to one terminal of a power supply unit 278 having its other terminal grounded at 220. The relay operating circuit is completed through an indicator control unit 240 which is operated by signals passed by a preceding selective-circuit. A reset switch 210 having normally open contacts is shunted across between arm 254 and blade 248. An additional fixed contact arm 252 is connected to energize signaling devices such as signal light 230 and buzzer 232 when blade 248 is in contact with arm 252. The movable blade is biased, as by the springiness of the blade itself, toward engagement with arm 252 but upon energization of relay 246, is pulled away from arm 252 and brought into contact with arm 254.

The indicator control circuit 240 is arranged as by any convenient or well-known construction to keep the relay 246 energized so long as the desired effective signals are not being received, and arm 248 is maintained in the actuated position shown. This causes the relay to hold its armature 248 out of contact with arm 252, and prevents operation of the indicator. Upon receipt of the selected signals the indicator control circuit is arranged to increase in resistance so that the relay becomes deenergized, and armature 248 springs back into contact with arm 252. This closes the energizing circuit for the indicator light and buzzer and at the same time opens the lock-out circuit between contacts 254 and 248. The indicators are accordingly kept actuated even though the reception of the selected signals is only momentary, and enables accurate notation of the fire alarm indication. When the indications are no longer needed, switch 210 can

be operated to momentarily close the shunting circuit. This energizes the power supply circuit to relay 246, if the selected signals are no longer being received. Armature 248 will accordingly be pulled over to the position shown in the figure, the indicator, light and buzzer will stop operating and the apparatus will be ready for the next fire alarm.

The circuit of Fig. 3 can be arranged to respond only to those modulation frequencies which are supposed to indicate the signaling of a fire alarm. This corresponds to the modulating frequency controlled by transfer unit 194 in the apparatus of Fig. 2. An additional indicator circuit such as those shown in Fig. 3 can be arranged to respond to the modulations controlled by transfer unit 193, but this indicator need not have the lock-out feature shown in Fig. 3 and furthermore need not have the buzzer 232, but may be of the same type shown in the above-identified application Serial No. 171,628. This last indicator will accordingly monitor the apparatus and give a warning indication whenever any portion of the line, signaling stations, power supply, etc., fails to operate properly.

Fig. 4 shows one highly effective form of indicator control circuit 240 for the combination shown in Fig. 3, and is constructed by merely reversing the signal and bias polarities for the corresponding indicator shown in Fig. 3 of application Serial No. 171,628. The bias will accordingly keep the relay control stage at a relatively low impedance until the negatively polarized rectified signal voltage is impressed on the input of this stage.

In place of the grid-circuit-opening control as shown at Figs. 1b and 2 for example, the alarm-sounding circuit at the remote modulator can be arranged to control the plate circuit of one or all of the electron-discharge oscillator or amplification stages. This is not preferred however since it subjects the alarm contacts to the action of higher voltages and currents. In the dual vibrator type of construction as shown in Fig. 2 for example, it is sometimes preferred to provide a separate oscillator stage for each vibrator unit so that all the vibrating reeds will be kept in operation at all times. This eliminates any delay that may be caused by the necessity of a stationary remote modulator reed to be brought into vibration of sufficient amplitude for proper operation.

For reducing the power consumption of the apparatus, the electron-discharge tubes used may be of the so-called battery operated type of vacuum tubes which have directly heated cathodes and provide the desired operation with a minimum of cathode-heating energy. In addition dry rectifiers or crystal diodes can be substituted for the two diode stages of tube 160 for example. Inasmuch as dry rectifiers and crystal diodes operate without requiring separate heating currents, they reduce the power consumption of the apparatus.

In place of the lock-out type of indicators described above, the control handles 22 may be arranged to automatically lock when brought into fire alarm indicating position. A special unlocking mechanism may be provided, and may even be key-controlled, to permit return movement of these handles. The return of the handles is readily effected by the fire fighting unit that answers the alarm.

If desired, the audible alarm signals may be operated by means of a set of relay contacts sep-

arate from those that operate the signal light. Since the audible signals need only be used to warn a watcher to look for the signal light, a single buzzer or gong can be connected for operation by all of the control relays individually. It is advantageous to have signal lights that are colored differently to indicate different operating conditions. Such an additional signal light can also be connected between contact 254 and ground in the construction of Fig. 3 to show that the relay is operating properly.

The alarm closing circuits need not be controlled by mechanically moving relay parts, but can be operated with electron-discharge tube controls. Thus, a warning light or buzzer can be substituted for the relay of Fig. 4 in the plate circuit of the electron-discharge control stage to which it is connected. The light (or buzzer) will accordingly be adjusted so that it remains lit at all times except when the selected signals are impressed on this stage. By having the light of the arc-discharge type and arranging so that the circuit does not have sufficient voltage to cause an arc to strike except when a special reset switch is operated, the light will automatically lock itself out.

A feature of the above forms of the present invention is the fact that not only are the apparatuses completely self monitoring, but there can be no confusion between any number of alarm signals even though they be sounded simultaneously. In each case an alarm is limited to a characteristic modulation frequency and can operate an individual visual indicator. Any number of alarms sounded at the same time will merely cause the actuation of the corresponding number of individual indicators, and simple observation will readily show which indicators are being actuated simultaneously.

Where installations have only a limited number of alarm stations, there is no need for the sharp selectivity of the more expensive contactless mechanically selective transfer units. In their place there can be used ordinary resistance-capacitance or inductance-capacitance types of oscillators such as those described in "Radio Engineers' Handbook" by F. E. Terman, Copyright 1943 by McGraw-Hill Book Co., Inc., Section 6, pages 480-484 and 503 to 511. The resistance-capacitance form of oscillator described on pages 505 and 506 is particularly suitable inasmuch as it dispenses with the need for an inductor which particularly at the lower carrier frequencies would be relatively expensive.

As many apparently widely different embodiments of this invention may be made without departing from the spirit and scope hereof, it is to be understood that the invention is not limited to the specific embodiments hereof, except as defined in the appended claims.

What is claimed is:

1. In a fire alarm system for use with a pre-existing line connected for transmitting low frequency electric currents for other purposes, carrier current supply elements for impressing high frequency electric currents on the line, a plurality of individual signaling stations each including a modulating unit, for connection to the line to modulate these high frequency currents, each station having three different modulating characteristics, said three modulating characteristics consisting of a constant first modulation to indicate an operative system, an absence of said first modulation to indicate a

fault or failure in the system, and a second type modulation to indicate the signalling of a fire, externally operable signal control structure connected to each station for operation to signal a fire alarm by changing the operation of the modulator unit to produce said second type modulation, and an indicator assembly for connection to the line to separately detect and indicate the presence of the individual modulation characteristics and thereby indicate the signalling and the source of specific fire alarms while simultaneously monitoring said system.

2. The combination as defined by claim 1 in which the individual modulator units include contactless mechanically selective elements connected for very accurately fixing the modulating frequency; and the indicator assembly includes a band-pass stage connected to selectively receive and pass a band of high frequencies including the modulation characteristics of all the individual stations, and contactless mechanically selective elements connected to sharply respond to the precise individual modulating frequencies.

3. The combination as defined by claim 1 in which each modulating unit includes a principal modulating frequency constituting said first modulation and a keying device connected for operation to repeatedly interrupt the modulation in a characteristic manner to produce said second type modulation.

4. The combination as defined by claim 3 in which the signal control structure of each station is connected to have a non-operated and an operated position, and to effect modulation at a characteristic frequency when in the non-operated position for thereby indicating that the system is in operating condition.

5. In a self-monitoring fire alarm system, a carrier current supply unit for connection to impress a high frequency electric current on a transmission line, a plurality of individual signaling stations each including a modulating unit for connection to the line to modulate the high frequency current, each modulating unit having two different characteristic modulating rates and including operable signal control structure connected for operation to signal a fire alarm by shifting the modulating rate from one to the other, and a central indicator assembly for connection to the line to separately detect and indicate the presence of the individual modulations for both monitoring the system and indicating fire alarm signals.

6. The combination set forth in claim 1 in which said transmission line is an electric power supply line.

7. The combination set forth in claim 1 in which said transmission line consists of a plurality of separate low frequency telephone lines and said central indicator is connected to each of said separate lines by high frequency band pass filtering units, said individual modulating units being connected to respective ones of said separate lines.
